UNITED STATES PATENT OFFICE.

STEPHAN GOLLOB, OF BOULDER, COLORADO.

DESIGN FOR A COMBINED DESK SET AND LAMP STAND.

Application filed October 19, 1925. Serial No. 15,180. Term of patent 14 years.

To all whom it may concern:

Be it known that I, STEPHAN GOLLOB, a citizen of the United States, residing at Boulder, in the county of Boulder and State of Colorado, have invented a new, original, and ornamental Design for a Combined Desk Set and Lamp Stand, of which the following is a specification, reference being had to the accompanying drawing, forming part thereof.

I claim:—

The ornamental design for a combined desk set and lamp stand, as shown.

STEPHAN GOLLOB.
